S. Brown.

Press for Printing in Colors.

No 12178.

Patented Jan. 2, 1855.

Fig. 2.

Fig. 1.

UNITED STATES PATENT OFFICE.

STEPHEN BROWN, OF SYRACUSE, NEW YORK.

PRESS FOR PRINTING DIFFERENT COLORS.

Specification of Letters Patent No. 12,178, dated January 2, 1855.

To all whom it may concern:

Be it known that I, STEPHEN BROWN, of Syracuse, in the county of Onondaga and State of New York, have invented a new 5 and Improved Press for Printing in Colors; and I do hereby declare that the following is a full, clear, and exact description of the construction and operation of the same, reference being had to the annexed drawings, 10 making a part of this specification, in which—

Figure 1, is a side elevation of my improved press. Fig. 2, is a longitudinal vertical section of same, the plane of section being through the center. Fig. 3, is a detached top view or plan of the sectional platens and the ways or grooves in which they work. Fig. 4, is a detached side view of the bed plate, one of the fingers and vibrating bar. 20 This view is designed to show the operation of the fingers and the manner in which the sheets of paper are fed to and from the sectional platens.

Similar letters of reference indicate corresponding parts in the several figures.

This invention relates to a new and improved press for printing in colors, whereby several colors may be printed at a single operation or at the same time.

30 The nature of the invention consists—

1st. In the employment or use of a series of platens which I term sectional platens. The form to be printed from is placed upon the several platens, and so arranged, that 35 each part of the form upon the several platens may receive the color desired. The platens work in grooves or ways in the sides of the press frame and rest upon stops at sufficient distances apart to allow the different ink rollers to pass over all the platens at the same time. The platens when 40 the form is inked are operated upon and pressed against the sheet simultaneously by a movable bed or platen which works underneath them.

45 2nd. My invention consists in the peculiar means employed for operating the movable bed or platen and ink roller.

3rd. My invention consists in a peculiar 50 manner of operating the fingers which grasp the sheets of paper and convey them to and from the form.

To enable others skilled in the art to make and use my invention I will proceed to describe its construction and operation.

A Figs. 1 and 2 represents the frame of the press which frame is of rectangular form and having at about its center a trans-

verse shaft B, placed within it, said shaft working in suitable bearings in the sides of 60 the frame.

On the shaft B, at about its center is placed a cam C, and at each end of the frame A, at its lower part are placed two transverse shafts D, E, the outer shafts E, E, 65 having arms F, F, attached to them. To the upper ends of these arms F, F, there are attached by jointed arms G, G, two horizontal bars H, H, two bars to each arm, the two bars of each arm being some distance 70 apart. At the end of each bar H, there is an ink roller I, secured or fitted in any proper frame or box J, and working in suitable bearings thereon. The frame or boxes being secured to the ends of the bars H, as 75 shown clearly in Fig. 2, and by dotted lines in Fig. 1. The frames or boxes H, work or fit in horizontal grooves (a) cut in the inner surfaces of the sides of the frame A.

On the inner shafts D, D, there are secured bent or right angled levers K, K, one on each shaft. The upright parts of these bent levers are attached by jointed levers or frames L, L, to the arms F, F, on the outer shafts E, E. The ends of the horizontal or 85 lower parts of the bent levers K, K, are connected together by a bolt (b) which passes through a slot (c) in one of the levers K, the bolt being permanently secured in the other lever K, and having a friction roller 90 (d) upon it, as shown by dotted lines.

The cam C, upon the shaft B, works directly over the friction roller (d) and at certain points in its revolutions acts upon it as will be hereafter shown.

95 The upper end of the upright part of one of the bent levers K, is provided with a segment M, against which the cam C, also acts at certain points in its revolutions. This will also be hereafter referred to more particularly.

100 Directly over the cam C, there is a bed or platen N, see Fig. 2, the ends of which have ledges or projections which fit or work in vertical grooves (e) the grooves being in the 105 inner surfaces of the sides of the frame. Underneath the bed or platen N, there is a friction roller O, which rests upon the periphery of the cam C, as clearly shown in Fig. 2.

110 P, P, P, are platens, on which the type to be printed from are placed. The type upon the several platens constitute the "form." The platens fit or work in vertical grooves (f) in the inner surfaces of the sides of the 115 frame, a small projection (g) being at each

end of the platens which projections fit in the grooves (f) as clearly shown in Fig. 3. The platens are supported at different heights in the grooves (f) by pins (h) as shown in Figs. 1, 2 and 3. And the position of the platens P and ink rollers I, are such that the rollers I, can pass over the whole number of platens and ink the type thereon at the same time.

- 10 To one of the upper frames or boxes J, which contains an ink roller, an adjustable bar Q is secured, see Figs. 2 and 4. This bar is secured to the box or frame J, by set screws (i) so that it may be set forward or 15 backward as desired. To this bar Q, fingers R, are secured, two or more. The fingers are formed of two jaws (j) (k) one of which (j) is attached permanently to the bar Q, the other jaw (k) is attached to the permanent jaw (j) by a pivot (l). A spiral spring (m) is placed between the two jaws by which the outer end of the jaw (k) is kept against the outer end of the jaw (j). To 20 the bar Q, and directly back of the jaw (k) a small spring catch (n) is attached.

S is a frame attached to one end of the frame A, by set screws (o) (o) so that it may be adjusted further in or out as desired. On the inner end of this frame S, a 30 bar T, is suspended, said bar having pivots at its ends which fit or work loosely in uprights (p) on the frame. The bar T, has small notches or recesses (q) cut in its under side and small spring pins or studs (r) 35 pass vertically through the bar, the lower ends of the spring or studs projecting a short distance below the under surface of the bar where the notches or recesses are cut, see Figs. 2 and 4. A small stud (s) is placed 40 in front of the bar T, at one end.

V, is a bed plate placed directly over the platens P, and secured at the desired point by screw V, as shown in Figs. 1 and 2. The bed plate has a screw (t) passing 45 through it, see Fig. 4; the use of this screw will be hereafter shown.

The type is placed upon the platens P, P, P, and motion being given the driving shaft Y, the cam C, is made to rotate and 50 first acts upon the friction roller (d) upon the bolt (b) and depresses the ends of the horizontal parts of the bent levers K, K, as shown by dotted lines in Fig. 1. This movement throws the ink rollers I, each of 55 which is charged with a separate and distinct color, across the platens P, P, P, the rollers moving in unison or at the same time, and inking the type on the several platens simultaneously. Each roller inking the type 60 on the platen which is in line with its motion. The cam C, now acts against the segment M, and throws the ink rollers back to their original position, as shown in Fig. 2, and the cam C, then raises the movable bed 65 or platen N, the cam bearing against the

friction roller O, and the bed or platen N, raises the sectional platens P, P, P, and forces them against the sheet which when receiving the impression is between the sectional platens P, P, P, and the bed plate V. 70 The impression it will be seen will be in different colors corresponding to the different colors of the platens P, and as the several platens P, are pressed simultaneously against the sheet, what formerly required 75 separate and distinct operations, is by my improvement performed in one operation.

The sheets of paper are fed to the press by the fingers R, attached to the bar Q, on one of the upper frames or boxes J, see Fig. 80 4. As the fingers are moved forward with the ink roller the lower end of the screw (t) depresses the back end of the upper jaw (k) which is caught and retained by the spring catch (n) leaving the jaws (j) (k) 85 open as shown by the dotted lines in Fig. 4. The fingers move forward over and beyond the platens in an open state till they pass under the bar T, at which point the fingers reach the sheet the edge of which passes between the jaws, and the spring pin or stud (r) throws the spring catch (n) off from the jaw (k) which closes by means of the spiral spring (m) and the fingers return with the sheet, the bar T, rolling or vibrating 90 backward to allow them to pass. The sheet being thus brought over the platens receives the impression and is then conveyed back with the return motion of the fingers and caught by the fly rollers. 100

The ink fountains and fly apparatus are not represented, as the usual devices are employed and they are well known to all press builders and require no description.

Having thus described my invention, 105 what I claim as new and desire to secure by Letters Patent, is,

1. The employment or use of a series of platens P, P, P, (two or more) arranged as herein shown or in an equivalent way, so 110 that the form or type on said platens may be inked simultaneously with separate and distinct colors and operated or pressed simultaneously against the sheet as set forth.

2. I claim the arrangement herein shown 115 of the cam C, bent levers K, K, and arms F, F, which are connected to the bent levers, for the purpose of operating the movable bed or platen N, ink rollers I, and fingers R as herein shown and described. 120

3. I claim operating the fingers R, by means of the screw (t) and rolling bar T, whereby the fingers are made to convey the sheet to and from the platens P, as herein described.

STEPHEN BROWN.
